UNITED STATES PATENT OFFICE

150,811

DESIGN FOR A DRESS

Marvin Satin, Chicago, Ill., assignor to H. A. Satin & Co., Chicago, Ill., a corporation of Illinois

Application November 6, 1947, Serial No. 142,332

Term of patent 7 years

(Cl. D3—26)

To all whom it may concern:

Be it known that I, Marvin Satin, a citizen of the United States, residing at Chicago, in the State of Illinois, have invented a new, original, and ornamental Design for a Dress, of which the following is a specification, reference being had to the accompanying drawing, forming a part thereof.

In the drawings:

Fig. 1 is a view of the front of the dress showing my design.

Fig. 2 is a view of the back of the dress.

I claim:

The ornamental design for a dress, as shown.
MARVIN SATIN.
